AUTOMATIC GUN

Josef Dobremysl, Cambridge, England

Original application January 21, 1941, Serial No. 375,166. Divided and this application March 31, 1942, Serial No. 436,989. In Great Britain January 25, 1940

10 Claims.

(Cl. 89—33)

The present application is a division of the parent application Serial Number 375,166, filed January 21, 1941. It relates to automatic guns of the type having a transversely sliding breech block co-operating with a breech block carrier capable of performing longitudinal movements in the gun.

The object of the invention is to provide improved means for loading the cartridges into the barrel chamber and for returning the empty cartridge cases back into the cartridge belt.

According to the invention an automatic gun of the type having a sliding breech block and a device for moving the cartridges from a cartridge belt into the barrel chamber and for returning the empty cartridge cases back into the belt is provided with a carriage mounted for movement longitudinally of the gun and actuated by a lever pivoted in the breech block carrier and having one arm operatively connected with said carriage and the other arm forked for co-operation with abutments.

The accompanying drawing shows in different positions an example of the cartridge transporting device according to the invention.

Figure 1 is a longitudinal section of the relevant part of the gun showing the transporting device in the initial stage of its forward movement.

Figure 2 is a side view of the actuating lever and abutments.

Figure 3 is a longitudinal section, similar to Figure 1 but showing the transporting device in another position, and

Figure 4 is a similar section showing the transporting device in the final stage of its forward movement.

The barrel 1 has in its rear part a suitable slot 1a for the sliding breech block 2. A firing pin 3 is housed in the breech block 2. The latter is provided with studs or projections 4 engaging and co-operating with guiding grooves 5 arranged in the breech block carrier 6 and serving to impart vertical opening or closing movements to the breech block 2 upon recoil or return movement of the carrier 6 respectively. The cartridge transporting device consisting of a carriage 7 carrying a cartridge extractor 8 is mounted for sliding movement on the upper part of the carrier 6. The extractor is provided with a hook 9 for engaging the cartridges 10 at their rim or rear end. An actuating lever 11 for the carriage 7 is journaled in the carrier 6. The lower part of the lever 11 is shaped as a fork, see Figure 2, one limb of which engages a fixed abutment or surface 12 on the bottom of the casing 13 of the gun and the other a pivotal or movable abutment 14. A recoil spring 55

15 for the breech block carrier 6 is mounted in the rear part of the gun.

The feeding movement of the cartridge belt may be derived from the barrel 1, which, as described in the specification of the concurrent application Ser. No. 375,166, filed January 21, 1941, imparts feeding movement to a feeding slide 21. The cartridge belt 16 may be of any desired type allowing full cartridges to be pushed out into the barrel 10 chamber and the empty cartridge cases drawn back by the extractor to be received again by the belt. In a preferred embodiment the cartridge belt may consist of links each consisting of an elastic sleeve 17 which holds the cartridge 10, the sleeve being secured to a carrying piece 18. The carrying pieces may be connected by any suitable means such as bolts, wire spirals, etc. Each link is provided with guiding projections 19 on its front and rear ends, said projections serving to guide and hold the link in position in the gun even when the link is empty.

The cartridges or the cartridge cases are supported along their path from the belt into the firing chamber and back again into the belt by supports 20, which may have the form of rods anchored in the barrel 1 and guided in the carrier 6.

A cover 22 may be mounted on the upper part of the gun to allow easy access to the operative parts of the mechanism. An abutment or the like 23 is arranged in the casing of the gun, said abutment co-operating with the rear end of the extractor 8, or with a suitable projection thereon in such a way that when the extractor during the recoil movement comes to the point where the empty cartridge case is fully drawn into the belt, the said projection, or the rear end of the extractor, abuts against the abutment 23 causing the extractor to swing out of engagement with the cartridge case, as shown in Figure 1.

40 The device according to the invention operates as follows:

When the gun has been cocked the position of the parts is as shown in Figure 1, i. e., the carrier 6 is retained in its rear position by a trigger pawl (not shown). The breech block is open and the carriage 7 is in its retracted position on the carrier 6. The lower part of the actuating lever 11 is directed forward and one limb of it abuts against the surface 12. The cartridge belt may now be inserted into the gun as far as a suitably arranged stop.

If the trigger is pressed, the carrier 6 is released for forward movement under the influence of the recoil spring 15. During the first part of the forward movement of the carrier 6 the lower end

of the lever 11 slides over the surface 12 so that the carriage 7 moves together with the carrier 6, see Figure 1. The extractor 8 engages the respective cartridge 10 and pushes it forward. The hook 9 springs behind the rim or into the groove of the cartridge. When the lower end of the lever 11 engages the abutment 14, see Figure 3, the lever 11 is rocked, as shown in dotted lines in Figure 3, and imparts to the carriage 7 and thus to the cartridge 10 an accelerated movement with regard to the carrier 6. The carriage 7 brings the cartridge 10 into the firing chamber and comes to rest, but the lever 11 rotates in clockwise direction, see Figure 4, because the carrier continues its movement. In the next stage of operation the carrier 6 closes the breech block 2 by means of the projections 4 and grooves 5. After the breech block has been closed the carrier still moves forward through a certain distance until it actuates the firing pin 3 and fires the cartridge.

After the shot has been fired, the barrel 1, the breech block 2 and the carrier 6 are moving backwards as one unit. After a certain distance the recoil movement of the carrier 6 is accelerated with regard to the barrel 1, in any desired manner, so that the breech block 2 is brought into the open position. The accelerated recoil movement of the carrier may be produced in the manner described in the specification of the parent application, Ser. No. 375,166, filed January 21, 1941.

The carriage 7 does not take part in the first stage of this accelerated movement of the carrier 6 and moves together with the barrel 1 until the empty cartridge case has been pushed out of the chamber by the primary extractor or releasing organ, (not shown). From this moment the carriage 7 begins to move quicker than the carrier in backward direction, because the lower arm of the actuating lever 11, which has already passed over the tiltable abutment 14 and tilted it out of its path, engages the surface 12 so that the lever is rocked in clockwise direction. During this movement the carriage 7 draws the empty cartridge case back into the belt, i. e., into that link of it, from which it was previously drawn out. During all its movements the cartridge or the cartridge case is supported by the supports 43. The carriage 7 continues its backward movement together with the carrier 6, until the rear arm of the extractor 8 strikes the abutment 23, see Figure 1, whereby the extractor 8 is rocked out of engagement with the cartridge case, after the latter has been drawn into its proper position in that link, from which it was originally pushed. The whole cycle of operations is then repeated. The device according to the invention may be preferably used with a gun of a type described in the specification of the concurrent application, Ser. No. 375,166, filed January 21, 1941, but is in no way limited to this particular application and may be used with any other type of gun of the kind hereinbefore set forth.

I claim:

1. An automatic gun comprising a gun casing, a gun barrel mounted therein, a breech block arranged in the barrel for sliding movement, a carrier mounted for movement longitudinally of the gun and adapted for co-operation with the said breech block, a cartridge belt for supplying into the gun of fresh cartridges which are to be brought into the barrel and for removing spent cartridge cases from the gun, means for moving cartridges from the cartridge belt into the barrel and for returning the spent cartridge cases back

into the belt, said means comprising a carriage mounted on the carrier for movement longitudinally of the gun, a lever pivoted in the carrier and having one arm operatively connected with the said carriage, and abutments in the said gun casing for co-operation with the other arm of the said lever.

2. An automatic gun as claimed in claim 1 wherein the lever arm co-operating with the abutments is forked shaped.

3. An automatic gun comprising a gun casing, a gun barrel mounted therein, a breech block arranged in the barrel for sliding movement, a carrier mounted for movement longitudinally of the gun and adapted for co-operation with the said breech block, a cartridge belt for supplying into the gun of fresh cartridges and for removing spent cartridge cases from the gun, a carriage mounted on the said carrier for movement longitudinally of the gun and for moving the full cartridges from the cartridge belt into the barrel and for retracting the spent cartridge cases back into the belt, a lever pivoted between its ends in the carrier and having one arm operatively connected with the said carriage and the other end forked, a fixed abutment adapted to co-operate with one limb of the forked arm of the said lever, a movable abutment arranged for co-operation with the other limb of the forked arm of the said lever, said movable abutment being adapted to engage the forked arm of the lever at the forward movement of the carrier but to be moved out of the path of the said forked arm upon backward movement of the carrier.

4. An automatic gun as claimed in claim 3 wherein the fixed abutment is adapted to engage the fork shaped lever in the rear part of the backward movement of the carrier to rock out the lever and accelerate the backward movement of the carriage in this stage.

5. An automatic gun as claimed in claim 3 wherein the fixed abutment is shaped as a guide of the forked arm of the lever for the last part of its backward and the first part of its forward movement.

6. An automatic gun as claimed in claim 3 wherein the movable abutment is adapted to co-operate and to rock out the said lever to impart to the carriage a forward movement accelerated with regard to the movement of the carrier during the forward movement of the latter.

7. An automatic gun comprising a gun casing, a gun barrel mounted therein, a breech block arranged in the barrel for sliding movement, a carrier mounted for movement longitudinally of the gun and adapted for co-operation with the said breech block, a cartridge belt for supplying into the gun of fresh cartridges and for removing spent cartridge cases from the gun, a carriage mounted on the said carrier for movement longitudinally of the gun, means on the fore part of the carriage adapted to engage the bottom of the cartridge and to move the latter from the cartridge belt into the barrel, an extractor mounted for rocking movement on the carriage and adapted to engage and grip the cartridge at its rear portion when its bottom is engaged by the said means on the fore part of the carriage, a lever pivoted between its ends in the carrier and having one arm operatively connected with the carriage and abutments in the gun casing adapted for co-operation with the other arm of the said lever.

8. An automatic gun as claimed in claim 7, means on the said extractor and means in the

casing of the gun for bringing the extractor out of engagement with the cartridge case after the latter has been drawn back into the cartridge belt.

9. An automatic gun comprising a gun casing, a gun barrel mounted therein, a breech block arranged in the barrel for sliding movement, a carrier mounted for movement longitudinally of the gun and adapted for co-operation with the breech block, a cartridge belt for supplying into the gun of fresh cartridges and for removing spent cartridge cases from the gun, a carriage mounted on the carrier for moving full cartridges from

the belt into the barrel and for retracting spent cartridge cases back into the belt, supports for the cartridges during their movement out of the belt into the barrel and for the cartridge cases during their return movement to the cartridge belt and means for imparting to the carriage of movements relatively to the carrier.

10. An automatic gun as claimed in claim 9, wherein the supports for the cartridges and cartridge cases consist of rods anchored in the barrel and passing through and guided in the carrier.
